CLAIM

The ornamental design for an air filter for vacuum cleaner, as shown and described.

DESCRIPTION

FIG. 1 is a top, front, right side perspective view of an air filter for a vacuum cleaner according to my new design; FIG. 2 is a front elevation view thereof; FIG. 3 is a rear elevation view thereof; FIG. 4 is a left side elevation view thereof; FIG. 5 is a right side elevation view thereof; FIG. 6 is a top plan view thereof; FIG. 7 is a bottom plan view thereof; FIG. 8 is a bottom, front, right side perspective view thereof; and, FIG. 9 is a top, front, left side exploded perspective view showing an environment of the vacuum cleaner air filter. The broken lines illustrate environmental matter and form no part of the claimed design.

1 Claim, 6 Drawing Sheets
